COMBINATION VOLUMETRIC BURETTE

Sol B. Wiczer, Washington, D. C.

Application June 5, 1950, Serial No. 166,159

5 Claims. (Cl. 222—158)

1

This invention is a continuation-in-part of my copending application Serial No. 557,471, filed October 6, 1944, now Patent 2,510,159, dated June 6, 1950, and relates to a volumetric measuring device and in particular to a combination volumetric burette and small vernier burette or micro-burette. In my parent application I have described a burette combined with a micro-burette whereby titration of chemical substances may be performed either with the ordinary burette or alternatively, with the micro-burette of the two burettes may be inter-connected to allow a combined titration whereby the titration through one burette may be more accurately read from the combined volumes after inter-transfer of fluid between burettes after titration.

According to the present invention the burette is constructed to allow a combined simultaneous titration for both burettes, the reading however, is obtained as combined volumes preferably from the micro-burette for extreme accuracy. Further, with the present construction, it is possible to titrate alone from the micro-burette.

Hence, with the construction herein improved titration is now possible because it is unnecessary to transfer fluid from the large burette to the small burette for a large burette titration in order to obtain micro-burette reading as disclosed in my parent application. It is only necessary to perform a large burette titration and take an immediate reading off the micro-burette for micro-burette accuracy.

It is accordingly the primary object of the present invention to provide a combination burette and micro-burette whereby titration may be directly effected as a combined titration with micro-burette accuracy.

It is a further object to enable this construction to be used in simple micro-burette titration. It is a further object to construct both burettes with completely automatic self-filling zero reading features from a common reservoir bottle. Other objects are inherent in the description hereof and drawings, as will be apparent to one skilled in the art.

In the drawings:

Fig. 1 shows an elevation of a combination burette and micro-burette assembly of the present invention with certain parts broken away and in section to show internal construction thereof.

Fig. 2 shows the reverse side of the micro-burette alone, indicating micro-burette calibration.

Fig. 3 is a section through the valve showing

the internal construction thereof taken on a line 3—3, Fig. 1, the position of the valve shown in Fig. 3 being that where both burettes are interconnected, but no fluid flows through the outlet.

Fig. 4 is a similar view to Fig. 3 showing the valve position with fluid from the micro-burette only.

Fig. 5 is a similar view to Figs. 3 and 4 showing the valve position when both burettes are flowing.

Fig. 6 is a perspective view of the disassembled valve plug to show detailed construction thereof.

Referring to Fig. 1 the burette assembly is shown mounted for automatic filling and comprises a large burette 10, constructed of glass, plastic or other transparent material which is not necessarily, but may be calibrated if desired, on its cylindrical surface for readings at 11.

The preferred accurate calibration is on the micro-burette so that the calibration as shown at 11 may be rough if desired. The lower part of the tube may taper to a shank at 12 and depend substantially to the bottom of a supply reservoir for chemical solution 13 which com-

prises merely a bottle having a bored rubber or cork resilient stopper 14 fitted into the neck 15 thereof for air tight reception and vertical support of the shank 12. For automatic displacement of the fluid from the bottle 13, a second tube

16 is fitted through a parallel bore in the stopper 14, which is open at the top 17 to vent the return supply of fluid and which has a side arm tube 18 connecting with a flexible aspirator bulb 19 conventionally constructed of rubber through a

connecting piece of rubber tubing 20. The shank of the burette 12 tapers to meet the burette at 21, but is substantially separated therefrom through a partition 22 communicating only with a capillary tube 23 connected to the top thereof

at 24. The upper end of the capillary tube 23 is sealed to a rounded bulb 25 comprising the top of the large burette at 26 for support of the upper end of the rather fragile capillary tube 23. Intermediate the ends, the capillary tube

25 curves at 27 and is open at an accurately cut portion of the curve at 28 which accurately defines the upper limit of fluid to which the large burette and interconnected micro-burette will be filled. The large burette is further provided with a vent 29, venting return of excess fluid to the supply reservoir 13.

The lower end of the burette 10, immediately above the partition 22, leads into a connecting tube 30 which communicates with one or more

passageways of a valve 31, comprising a tapered

2

wall 32 having close fit as by grinding therein for free, but fluid tight rotation a valve plug 33. Vertically sealed to and rising from the valve assembly 31 and parallel to the large burette, is a micro-burette comprising a capillary tube 34, which consists of an accurately bored capillary tube having a total of only about 1 to 5 cc., generally about 2 cc. of liquid capacity. The micro-burette 34 is fastened at the upper end to the large burette by any supporting means such as a fragment of glass 35, comprising a bracket, preferably of plastic or glass sealed at each end respectively to the top of the micro-burette and to the large burette. The micro-burette is opened at the top at 36 communicating thereby with the atmosphere. The micro-burette is calibrated on the front surface with micro-burette accuracy at 37, such calibration corresponding to the combined volumes of both burettes such that a reading taken from the micro-burette will indicate the volume of fluid that has passed out of the apparatus in a titration from both burettes. On the reverse side of the micro-burette is another calibration 38 as shown in Fig. 2, such calibration being the calibration of the volume of the micro-burette alone.

Extending forwardly from the valve casing 31, as better shown in Fig. 3, is an outlet spout 38, a tube which tapers to a narrow tip 39, to allow visible accurate dropwise release of liquid. Control of fluid flow is in the multi-way valve plug 33 which is broken away in Fig. 1 to show the general mounting of the valve plug as well as some of the internal ducts thereof. In the position shown in Fig. 1, the valve plug is set merely to inter-connect both burettes through a groove-like duct 40 which may be merely a shallow gouge cut in the tapered surface of the valve plug 33, sufficient to allow fluid to easily flow from the large burette to the small burette. In this position no fluid can enter the outlet spout 38. Fig. 3 is an elevation in section through the valve showing this position thereof.

For further control of the fluid flow for operation of the combination of burettes and as best seen in Fig. 6, valve plug 33 is bored with two radial ducts 43 and 44 at about the center of the plug 33 which connect with each other at substantially right angles and lead radially from the center of the plug 33 to the periphery for alternate inter-connection thereof with the central outlet spout 38. When the valve plug is rotated in the direction of the arrow on knob 45 of Fig. 6 90°, two radial bores 46 and 47, which similarly are bored from the periphery to a center portion of the plug 33 and which are inter-connected with both outlets 43 and 44 through a longitudinal bore 48 are thus placed by rotation to the vertical position, so that each of bores 46 and 47 are aligned with the micro-burette 34 and large burette 10 respectively. In such position duct 43 is aligned with the outlet 38 so that both burettes are connected to the outlet for simultaneous discharge of fluid. (See also Fig. 5.)

Still another duct 49 is bored from the periphery to interconnect with ducts 43 and 44 through the central duct 48 and is further aligned with duct 46 so that when the knob 45 is completely reversed, i. e. at 180° rotation from the position shown in Fig. 1, the duct 49 alone will interconnect with the micro-burette 34. At this position duct 44 will have been aligned with the outlet spout 38 so that now the titration is possible from the micro-burette alone. (See also Fig. 4.)

Cross sectional details showing the valve posi-

tion when both burettes are flowing is shown in Fig. 5 and with the micro-burette alone is shown in Fig. 4.

In automatic operation and with the valve set as shown in Figs. 1 and 3, when the operator places his finger over the vent 17 and introduces air pressure into supply bottle 13 by squeezing the aspirator bulb 19, fluid will flow through the tube 12, into the capillary tube 23, and into the large burette through the capillary outlet 28, and thence into both burettes 10 and 34 by way of passages 30 and 43, filling the same. After the fluid has passed into both burettes above the zero reading, operation of the aspirator bulb 19 is stopped, the vent 17 is freed, and the fluid will return automatically through capillary opening 28 returning excess fluid to the supply bottle 13 by way of capillary 23, until the fluid stands exactly at zero mark of the calibration.

For a large volume titration, rotation of the plug from the position of Fig. 1 in the direction of the arrow shown in Fig. 6 will align outlets to both burettes by way of now vertically positioned ducts 46, 47 and horizontally positioned outlet 43, so that fluid will pass through the outlet tip 39 until the chemical analysis has been completed. The outer calibration 37 on the micro-burette is such that the reading of the fluid level therein after titration will give an accurate reading of fluid volume discharged from both burettes which will be read through the capillary size meniscus of the micro-burette thus giving extreme accuracy for a large volume titration.

When it is desired to titrate with the micro-burette alone, then after filling both burettes as described from the position of Fig. 1 the valve is rotated in the opposite direction to the knob arrow of Fig. 6 to bring outlet duct 49 vertically into communication with the micro-burette 34 while the central duct 44 communicates with outlet 38 as shown in Fig. 4. Thus, titration is effected from the micro-burette alone and in this instance the reading may be obtained from the reverse side of the micro-burette calibrated at 38 as shown in Fig. 2 to obtain a micro-burette titration and reading thereof.

As thus described it is possible with the combination herein shown, to obtain in a large volume titration all the advantages of extremely accurate reading from a calibration upon a micro-burette tube, or when a micro-burette titration is desired alone, such titration may be effected independently.

Various modifications in burette construction may be substituted from practices otherwise known in the art. For example, and as pointed out in applicant's parent application, the burette and micro-burette may be modified to avoid automatic filling where this is desired. For this purpose the automatic filling shank is removed and the bottom rounded off, the internal capillary tube 23 is removed and the enclosing portion 25 thereof at the top of the large burette 10 may be removed to allow open top construction for merely pouring fluid into the top thereof.

Similarly, the cutting of ducts, 46, 47, 48, 49, 43 and 44 may be such as is conventional in the art, that is, the glass plug 33 may have its ducts cut at angles other than shown. For example, it is merely necessary to interconnect ducts 46 and 47 with the outlet 43; and duct 49 with the outlet 44; so that, rather than cut deeply into the body of the valve plug 33, the same may be accomplished by merely cutting peripheral grooves, whichever is more convenient for inter-

connecting these ducts. Large scale rough calibration is shown on the large burette 10. Such calibration is a mere convenience; it may be rough or accurate as desired, to give the operator at least a rough idea of how much fluid to release quickly before the alternate slow release of fluid as the end point is approached. However such calibration on the large burette is not essential for the operation of this device.

It is accordingly intended that the specific embodiment herein set forth in the drawings be regarded as exemplary and not limiting except as defined in the claims.

I claim:

1. In combination a volumetric chemical analysis burette of relatively large volume and a burette of relatively small volume, each comprising elongated transparent tubes, the small volume burette having a calibration indicating the volumetric contents of the combined volumes of both burettes, a discharge spout comprising a tube drawn to a capillary point for dropwise effluence of liquid, a rotary multi-way plug valve communicating with both burettes and with said discharge spout, said multiway valve comprising a rotary plug having passageways therethrough interconnecting both burettes to each other only in one position thereof, interconnecting both burettes to each other and simultaneously with the outlet in a second position of the plug, and interconnecting only the smaller burette with the outlet in a third position of the plug.

2. The burette construction as claimed in claim 1, wherein the burette of small volume has two calibrations, the first measuring the combined fluid volume of both burettes and the second

measuring the combined fluid volume of the smaller burette alone.

3. The burette construction as claimed in claim 1, wherein each burette has a calibration measuring the combined fluid volume of both burettes, and the smaller burette has an additional independent calibration measuring the fluid volume of the small burette alone.

4. The burette construction as claimed in claim 1, wherein both burettes have means for automatically filling the same.

5. The burette construction as claimed in claim 1, wherein the large burette has a volume not exceeding about 100 cc. the burette of smaller volume is a micro-burette having a total volume of 1 to 5 cc.
